CLAIM

I claim the ornamental design for my artificial flowers, as shown and described hereinbefore.

DESCRIPTION

FIG. 1 is a side elevation of a flower, in accordance with the invention.

FIG. 2 is a view of the right side of the flower in FIG. 1.

FIG. 3 is a view of the flower in FIG. 1 from above.

FIG. 4 is a side elevation of a second embodiment of the invention.

FIG. 5 is a view of the right side of the embodiment in FIG.

4.

FIG. 6 is a view of the embodiment in FIG. 4 from above.

FIG. 7 is a side elevation of a third embodiment of the

invention.

FIG. 8 is a view from the right side of the embodiment in FIG. 7; and.

FIG. 9 is a view of the embodiment in FIG. 7, taken from

above.
